HANDLE FOR SCREW DRIVERS OR THE LIKE

Clarence L. Dewey, Grand Rapids, Mich.

Application December 23, 1946, Serial No. 718,069

1 Claim. (Cl. 145—61)

1

My invention relates to a small tool adapted for manual operation. In the embodiments herein shown and described, the tool takes the forms of a screw driver, and of a chisel. It will be understood that these particular forms of tool are merely illustrative of several—push drills, socket wrenches, are others—with any one of which my invention may be advantageously used.

The special features of construction which characterize my invention reside largely in the form and construction of the handle which is shaped for convenient manual operation, and in the connection therewith of a bit or other work-engaging part. The two together make up a simple tool which is very strong so as to transmit both percussive and torsional forces without damage to the implement. These and other objects of my invention may be realized from the tool structure illustrated in the accompanying drawing in the manner following wherein:

Fig. 1 is a side elevation of the portion of the tool adjacent its work-engaging end;

Fig. 2 is an elevation of the tool in its entirety, from a position 90° around from that of Fig. 1;

Fig. 3 is a transverse section, greatly enlarged, taken on line 3—3 of Fig. 2;

Fig. 4 is a cross section through the tool handle in a plane proximate to the user's fingers when in grasping relation thereto;

Fig. 5 is a side elevation of the work-engaging angularly extending end portion of a handle adapted for support of a chisel tool;

Fig. 6 is a longitudinal section through a tool whose hollow handle at one end is fitted with a removable cap, the opposite tool end being formed with a chuck for support of a selected tool;

Fig. 7 is a transverse section, taken on line 7—7 of Fig. 6; and

Fig. 8 is a view in elevation of the chuck end of the tool.

The tool comprises a handle H operatively connected at one end to a work-engaging part, such as a bit B of hardened steel. The term "bit" will, for convenience, be used hereinafter to designate any such work-engaging part, and I ask that it be so understood. The handle is made of tubular metal, desirably aluminum.

Referring first to the construction of Figs. 1 and 2, the handle H comprises a grip 6 adapted for fitting in the palm of the hand; at its outer end the grip is inwardly tapered and then rounded over at 7 to provide a closed end which will be comfortable to the palm when end pres-

2

sure is applied to the tool. At the opposite end the grip 6 tapers inwardly at 8 to join with a finger-engaging portion 9 and then inwardly again at 10 to continue on in the form of a cylindrical shank 11.

The grip 6 is formed with a plurality of longitudinally extending flutes produced by inward depressions a which lie between outward projections b. The contour of these flutes presents a series of in and out curves as best shown in Figures 2, 3, and 4. When grasped by the hand, the encircling fingers and also the thumb may readily be fitted within the flutes thereby to effect a positive grip on the handle.

15 The shank 11 terminates in a flattened head 15. This change in form may be conveniently produced by appropriate dies which apply pressure from opposite sides of the shank. The head so formed is widened outwardly beyond the confines of the shank in one plane and narrowed inwardly thereof in a transverse plane—see Figs. 1 and 2. The head defines within itself a socket which is elongated in a direction which is diametric of the shank axis. At the inner end of 20 the socket is a constriction formed by opposed shoulders 16 which are disposed substantially in the plane of juncture between the head and the shank.

25 The bit is provided with a cross sectional contour substantially the same in size and shape as the socket within the head whereby to fit properly therewithin. The inner end 17 of the bit is free to advance as far as the shoulders 16 which serve as an abutment therefor. The bit may be locked in place as by brazing, welding, or by dimpling inwardly the head at points 20 opposite each other and opposite a hole 21 which is extended transversely through the bit. The inwardly displaced material of the head resulting from the 30 dimples will then enter partly into the bit hole 21 so as to lock the bit fixedly in its operative position.

35 In use, whether the tool be used as a percussion instrument or for transmitting torsional forces, the bit is amply supported to withstand the strains of use. This comes about from the fact that the inner end of the bit is supported against the shoulders formed at the juncture of the head with the shank of the tool, and by the fact that the metal contained in the tubular wall of the shank is flattened at the end into the form of a head to provide a socket the same in contour as the bit which it is designed to accommodate. 40 The interlock between the bit and head which is

a permanent one may be produced in any of the ways suggested.

In the construction suggested in Fig. 5, the shank 11 at approximately its point of juncture with the flattened head 15 is angled at 16 whereby the supported bit B is disposed angularly with respect to the axis of the shank. Such a special construction may be advantageous in the case of chisels, or a wood carving set. The chisel point, which is comparable in all respects with the bit B, may be fitted within the socket of the head and retained therein in precisely the same way as already described.

Coming now to the construction of Figs. 6-8, I have shown here a tubular handle H comprising a grip 26 which is tapered inwardly at 28 to join with a finger-engaging portion 29 and then inwardly again at 30 to continue on in the form of a cylindrical shank 31. In the process of drawing the handle to shape, I provide for walls of maximum thickness in the region of the cylindrical shank 31, thinning slightly through the tapering region 30 so as to be still thinner in the finger-engaging portion 29. From this point on the walls are further reduced in thickness through the region of the grip 26, which near its outer end is constricted inwardly and formed with screw threads 32 to receive engagement from the threaded sides 33 of a closure cap C adapted, upon occasion, to be removed for access to the hollow chamber within the handle.

A plug 35 is secured within the hollow interior of the cylindrical shank 31 so as to establish a closure for the inner end of the chamber within the handle. This plug may be held by a drive fit, or otherwise. Beyond the plug the walls of the shank are longitudinally slotted at 40 to provide multiple jaws 41 of segmental form which may be compressed toward each other to engage between them the shank s of a tool B, such as a chisel point, a file, etc.

Formed exteriorly upon the segmental jaws are taper threads 45 whereon may be adjustably secured a polygonal chuck 46 which may be operated as by application of a wrench. This chuck is provided with an axial opening 47 through its outer end for lateral support of the shank of the engaged tool which is operatively positioned between the jaws. A satisfactory degree of resiliency for these jaws and an adequate strength for the threads 45 will be assured if the tubular structure be formed from metal having suitable properties, such as steel, for example. By so disposing the metal that the maximum wall thickness is in the shank where the jaws are formed, it is possible to produce the taper threads 45 by a cutting operation—the most desirable way.

In the tool under description, the grip may be contoured with flutes, or be cylindrical, according

as may be preferred. It embodies the desirable feature of a light-weight, yet very strong, tubular handle having an interior chamber to which access may readily be gained for insertion or removal of the tool points, together with an arrangement of compressible jaws at the opposite end adapted to be operated in response to movement of the chuck. The plug 35 which establishes a bottom for the chamber within the handle also furnishes an abutment against which may rest the butt end of the tool point.

It is obvious that tools answering to these descriptions will be rugged in the extreme. They will combine this desirable attribute with lightness as well. They may also embody in their handle some pleasing contours resulting from the presence of the flutings which make for an enhanced gripping power when in the hands of the user; these flutings also prevent rolling of the tool. Whether the tools be handled carelessly or otherwise, they may be depended upon to perform as an effective mechanical instrument over an extended period of use.

I claim:

25 A manual tool of tubular form from end to end made from a continuous piece of tubular metal progressively reduced in diameter to provide an enlarged upper grip section, an intermediate finger engaging section, and a lower shank section terminating in a flattened head formed to receive and laterally support a bit whose work-engaging end is projected outwardly therebeyond, said flattened head having opposite portions thereof pressed radially inwardly for tight engagement 30 with the supported bit at spaced points therearound to secure the bit fixedly in operative position, the flattened head extending outwardly beyond the confines of the shank in one plane and narrowed inwardly thereof in a transverse plane and thus forming an abutment inwardly of the end of the flattened head with which the bit may engage, whereby to transmit thereto a thrust proceeding axially of the tool toward the work.
